[57] **CLAIM**

The ornamental design for fixing rail, as shown and described.

DESCRIPTION

FIG. 1 is a top view of the fixing rail showing my new design;

FIG. 2 is a bottom view thereof;

FIG. 3 is a side view thereof with the opposite side view being identical in appearance;

FIG. 4 is a cross sectional view through Section IV—IV of FIG. 1;

FIG. 5 is a cross sectional view through Section V—V of FIG. 1;

FIG. 6 is a left end view thereof, the right end view being the same and, therefore, not shown; and,

FIG. 7 is a top/left end/side perspective view thereof. The claimed design is shown broken away to indicate indeterminate length.
